Primary Examiner — Kevin K Rudzinski*Assistant Examiner* — James P Mckane(74) *Attorney, Agent, or Firm* — Bold IP, PLLC;
Christopher Mayle(57) **CLAIM**

The ornamental design for a magnetic headband insert as shown and described.

DESCRIPTION

FIG. 1 is a perspective view of a magnetic headband insert showing our new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is a perspective view of the magnetic headband insert inserted into a hat.

The broken lines in the drawings represent attachment accessory portions of the magnetic headband insert that form no part of the claimed design.

1 Claim, 5 Drawing Sheets(56)
